BARBEQUE GRILL OR THE LIKE

Bailey C. Williams, 1200 Marlboro Road,
Raleigh, N.C. 27610

Filed Aug. 18, 1966, Ser. No. 3,521

Term of patent 14 years

(Cl. D81—10)

FIG. 1 is a perspective of a barbecue grill or the like showing my new designs; and

FIG. 2 is a rear elevational view thereof, the legs being fragmentarily shown for convenience of illustration.

What is claimed is:

The ornamental design for a barbecue grill or the like, as shown.
